UNITED STATES PATENT OFFICE.

CLARENCE B. STURGES, OF SCRANTON, PENNSYLVANIA, ASSIGNOR OF ONE-HALF TO
J. GARDNER SANDERSON, OF SCRANTON, PENNSYLVANIA.

CARBURETER.

No. 918,607.

Specification of Letters Patent.

Patented April 20, 1909.

Application filed April 22, 1907. Serial No. 369,679.

To all whom it may concern:

Be it known that I, CLARENCE B. STURGES, a citizen of the United States, residing at Scranton, in the county of Lackawanna, in 5 the State of Pennsylvania, have invented a certain new and useful Improvement in Carbureters, of which the following is a specification.

This invention relates to carbureters for 10 gas engines.

Gasoline engine manufacturers and automobile builders have found that to get a thorough mixture, which is very essential to the smooth running of an engine, a vaporization 15 of the gasoline with a certain proportion of air is required. To accomplish this, nearly all the carbureters are provided with a fuel nozzle and a float, the latter of which keeps the gasoline just at the top of the fuel 20 nozzle without overflowing. The air, rushing by the fuel nozzle, draws out the gasoline and mixes with it. This form of carbureter is objectionable for use on automobiles as the gasoline level in the fuel nozzle changes as 25 the automobile moves on different grades. Further, the float sometimes sticks and works hard. Thus, in both instances, the proportion of air and gasoline in the mixture is varied. A still further reason that 30 the proportion of air and gasoline varies is that the size of the gasoline discharge opening remains the same, that is, it does not increase when the amount of air increases and decrease when the amount of air decreases. 35 Consequently, when the air is predominant, a knock takes place at the end of the power stroke due to the too rapid fall of pressure in the cylinder and when the gasoline is predominant it carbonizes in the cylinders.

40 The object of my invention is to provide a carbureter that will always maintain the same and proper proportion of air and gasoline in the explosive mixture.

Other and further objects of my invention 45 will appear in the following description and will be more particularly pointed out in the appended claims.

In the drawings, Figure 1 is a side elevation of my invention. Fig. 2 is a vertical 50 section on line 2—2, Fig. 4. Fig. 3 is a vertical section on line 3—3, Fig. 4. Fig. 4 is a horizontal section on line 4—4, Fig. 2.

Referring more particularly to the drawings, 1 indicates the gasoline supply pipe 55 having a vertical discharge 2 at right angles

thereto and provided with a clean out plug 3 in alinement with the discharge. Surrounding the gasoline discharge 2 is a constantly open air chamber 4 which is provided with a contracted discharge mouth 5 located slightly 60 above the upper end of the gasoline discharge, so as to act as an ejector for the gasoline. The constantly open air chamber 4 is constantly open to and discharges, by means of its mouth 5, into a second air chamber 6. 65 This second air chamber is of cup-shaped formation and has depending therein a mixing chamber 7. As a method of manufacturing the carbureter, the air chamber 6 may be cast in one cup-shaped piece, while the mixing chamber may be cast onto a plate 8 which forms the top of air chamber 6, this top being provided with an opening 9 having an inwardly seating valve 10. Valve 10 is held normally closed by a helical spring 11, 70 the tension of which may be regulated by nut 12 on a screw threaded rod 13 which is secured to the valve 10 and passes through a spider 14 supported on top of 8. The mixing chamber 7 communicates with the valved air 75 chamber 6 by means of a contracted opening or passage 15 formed by a flange 16 depending from the mixing chamber directly over the contracted discharge 5 of the constantly 80 open air chamber 4, the mouth or inlet of the mixing chamber 7 being of greater diameter than that of the discharge 5. The mixing chamber is provided with an outlet 17 which may be connected to the cylinder of an explosive engine so that the cylinder is 85 constantly open to the mixing chamber. 90

The gasoline supply is controlled through a rod 18 having its lower end provided with an elongated tapering needle 19 of a length sufficient to remain in the discharge 2 for any 95 position of the needle. At the junction of the needle and the rod, a shoulder 20 is provided to rest upon the end of the discharge and prevent any binding action of the needle. The rod 18 is guided at its upper end in a 100 sleeve 21 adjustable axially through a packing 22^a on a cap 22 which closes an opening in plate 8, said opening permitting access to the mixing chamber. The adjustment of the sleeve is under the control of the operator by 105 means of a lever 25 pivoted intermediate of its ends to a bifurcated plug 26 fitting in the outer end of the sleeve. The lever is pivoted at one of its ends to one end of a link 27, the other end of the link being pivoted at 28 to 110

the top of the plate 8. The other end of the lever 25 is depressed in any suitable manner as for instance by breaking the joint of a toggle 29 which is pivotally connected to this 5 end of the lever and to the plate 8. The toggle is broken by a reciprocating rod which is controlled in any suitable manner by the operator.

Rod 18 carries a disk 23 which is rigidly 10 secured to the rod within the mixing chamber and is positioned so as to act as a valve to close the inlet 15 when the gasoline discharge 2 is closed or when the sleeve 21 is lowered to throttle the supply of gas to the 15 engine. The rod 18 is held in a position to close the gasoline discharge and the mixing chamber inlet by a helical spring 24 which bears at its upper end against the sleeve 21. It is apparent that the tension 20 of this spring may be regulated by adjusting the sleeve 21 axially and that the amount of mixture admitted to the engine is regulated by the movement of the sleeve.

The operation of my invention is as follows: The needle valve is opened when the 25 sleeve is in raised position and when a suction is created in the working cylinder of the engine, as the mixing chamber is constantly open to the working cylinder. This is due 30 to the fact that the suction will act on the disk 23 and move the rod 18 against the action of the spring 24. If the suction is great, the needle valve will be drawn a great 35 distance out of the gasoline discharge and vice versa. As the needle valve is of tapering form, it is apparent that the size of the gasoline discharge will be proportional to the suction. When the needle valve opens the gasoline discharge, the suction acts on 40 the air within the chamber 6, creates a vacuum therein and thereby drawing air from the air chamber 4. The air chamber 4 having a contracted mouth 5 surrounding the gasoline discharge 2, causes the air to 45 pass by the gasoline discharge with great force like an ejector and to take an amount of gasoline, this amount being dependent upon the suction which controls the size of the gasoline discharge. Should the suction 50 be very great, the valve 10 will open and admit an additional air supply. This valve 10 being regulable, it is apparent that the movement of the disk may be controlled thereby and consequently the opening of the 55 gasoline supply controlled. It will be noted that I thus provide a divided air supply, one branch of which mixes with the gasoline, and the other branch of which mixes with the mixture. The mixture of air and gasoline, after passing through passage 15 strikes the disk 23 which causes a disintegration of any small particles of gasoline and a consequent thorough mixture. From the mixing 60 chamber it passes through the outlet 17 to the engine.

Of course the air supply chamber 4 may be formed integral with the cup shaped chamber 6 instead of separate therefrom, as shown in the drawings. Further, the particular form or shape of parts shown 70 in the drawings may be varied.

Having thus described my invention, what I claim and desire to secure by Letters Patent is:

1. The combination with a gasoline supply pipe provided with a nozzle, of an air supply chamber surrounding the gasoline supply pipe and provided with a contracted mouth a little above the mouth of said nozzle, a second air chamber into which the air and the gasoline are discharged, a needle valve for regulating the flow of gasoline to the second air chamber, and a suction operated disk for controlling the flow of the mixture into a mixing chamber; said valve 85 and disk being carried by the same rod.

2. The combination with a gasoline supply pipe provided with a nozzle, of a valve for controlling the flow of gasoline therefrom, an open air-chamber surrounding the gasoline supply pipe and provided with a contracted discharge opening above said nozzle, a valved air chamber into which the gasoline and air are delivered, a mixing chamber, and a suction operated valve 95 adapted to control the flow of gasoline and air from the valved air chamber to the mixing chamber; the valve for controlling the flow of gasoline from the gasoline supply pipe being operated by said suction operated 100 valve.

3. The combination with the gasoline supply pipe provided with a nozzle, of an air supply pipe, surrounding the same and adapted to form an ejector for the gasoline 105 above said nozzle an air chamber into which the gasoline and air are discharged, a suction controlled disk for controlling the flow of gasoline and air from said air chamber; said disk being provided with a needle valve 110 whereby the discharge of gasoline from its pipe is regulated to correspond to the degree of suction in the engine cylinder.

4. The combination with a gasoline supply pipe provided with a nozzle; of an air-supply chamber inclosing said supply pipe; another air supply chamber above the first-mentioned air-chamber and provided with an upper discharge opening; a contracted discharge-opening forming a communicating 120 channel between said air-chambers and adapted to act as an ejector for the gasoline from its pipe; and a suction-operated valve normally closing said upper discharge opening and provided with means for shutting 125 off the supply of gasoline when in its normally closed position.

5. The combination with a gasoline supply pipe provided with a nozzle; of an air supply pipe acting as an ejector for the nozzle 130

zle of said gasoline pipe; an air supply chamber above said ejector and provided with an opening through which the mixture is delivered thereto; a valved inlet in said air chamber whereby a supplemental admission of air is provided for; a mixing chamber communicating with the valved air-supply chamber; and a suction-operated valve normally closing said communication and provided with a needle valve whereby the flow of gasoline is regulated to correspond with the amount of opening of the suction operated valve.

6. The combination with a gasoline supply pipe, of an air supply pipe, acting as an ejector for the gasoline supply pipe, an air chamber above said ejector and provided with a supplemental air-inlet, a mixing chamber having a flange depending downwardly into the air chamber and forming a passage for the mixture delivered from the air chamber, and a suction valve mounted above the flanged opening to control the flow of mixture therethrough.

25 7. The combination with a gasoline supply-pipe and a suction controlled valve for controlling the flow of gasoline therefrom; of upper and lower air-supply chambers, said lower chamber being adapted to act as an ejector for the gasoline supply and said upper chamber being adapted to provide a supplementary supply of air to the mixture; a mixing chamber above said air chambers and adapted to receive the mixture therefrom; and means connected with said suction-controlled valve for controlling the flow of mixture into said mixing chamber.

8. The combination with a gasoline supply pipe, of a mixing chamber above the same and provided with a depending flanged opening for receiving the gasoline from its supply pipe; a suction valve for controlling the flow of gasoline and air through the flanged opening; and a source of air supply divided into two branches, one of which acts as an ejector for the gasoline from its supply pipe and the other of which introduces air into the mixture so formed.

9. The combination with a vertical gasoline supply pipe provided with a nozzle; of an air-supply pipe provided with an ejector above the nozzle of the gasoline supply pipe, a suction controlled valve varying the size of the discharge opening in the gasoline supply pipe and a valved air chamber for supplying additional air to the mixture in such

manner as to cause a regulation in the flow of gasoline.

10. The combination with a gasoline supply pipe, of a constantly open air supply pipe, acting as an ejector to the gasoline supply pipe, a mixing chamber, a valve controlling the inlet to the mixing chamber and carrying a needle valve for controlling the discharge of gasoline from its pipe, and a valved air chamber interposed between the first air supply and the mixing chamber.

11. The combination with a gasoline supply pipe, of an air supply pipe acting as an ejector for the gasoline supply pipe, a suction controlled valve for controlling the supply of gasoline, and means for regulating the movement of the suction controlled valve, said means comprising a sleeve carried by the valve-rod of said suction-valve a spring also mounted on said valve rod between the sleeve and the valve, an oscillatable rod pivoted thereto, and means for oscillating said rod.

12. The combination with a gasoline supply-pipe provided with a nozzle; of an air supply pipe acting as an ejector for said nozzle; a suction-controlled valve for controlling the gasoline supply; and means for regulating the movement of the suction-controlled valve, said means comprising a sleeve slidably mounted upon the stem of said suction-controlled valve, a resilient member interposed between said sleeve and the valve, a lever pivotally connected with said sleeve, and a toggle for moving said lever.

13. The combination with a gasoline supply pipe, of a constantly open air supply acting as an ejector to the gasoline supply, a mixing chamber, a valve provided with a valve rod for controlling the inlet to the mixing chamber, a sleeve slidable on the valve rod, a spring mounted on said valve rod between the sleeve and the valve, a freely movable lever pivoted to said sleeve, and a toggle-jointed lever connected with the former lever at one end in such manner as to adapt it to raise and lower the sleeve upon the valve rod.

The foregoing specification signed at 105 Scranton, Penna., this 26th day of November, 1906.

CLARENCE B. STURGES.

In presence of two witnesses—
